(57) **CLAIM**

The ornamental design for a chain saw, as shown and described.

DESCRIPTION

FIG. 1 is a perspective view of my new design for a chain saw;

FIG. 2 is a rear view thereof;

FIG. 3 is a front view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines shown in the drawings form no part of the claimed design.
